UNITED STATES PATENT OFFICE.

BERRY A. BAXTER, OF MANSFIELD, OHIO, ASSIGNOR TO NEW METHOD STOVE COMPANY, OF MANSFIELD, OHIO, A FIRM COMPOSED OF HENRY H. SANFORD, BERNHARD R. AHRENT, EDWIN D. BAXTER, AND BERRY A. BAXTER.

STOVE.

1,228,519.

Specification of Letters Patent.

Patented June 5, 1917.

Application filed August 19, 1915. Serial No. 46,238.

To all whom it may concern:

Be it known that I, BERRY A. BAXTER, a citizen of the United States of America, residing at Mansfield, in the county of Rich-
5 land and State of Ohio, have invented cer-
tain new and useful Improvements in
Stoves, of which the following is a specifica-
tion.

This invention relates to stoves, prefer-
10 ably of the type commonly known as heating
stoves which are constructed and
equipped for burning gaseous fuels.

The primary object of the present invention
15 is to so construct and design a stove that
at the point of the emission and igniting of
the gaseous fuel a constantly moving current
of air will be conducted from beneath and
above the flame simultaneously, thereby in-
suring perfect combustion with the resultant
20 economizing of operation, increase in heat
radiation and the elimination of the odor
which impregnates, poisons and vitiates the
air.

A further object is to construct a stove in
25 such a manner as to create a suction through
the medium of the draft arrangement which
will continually draw and circulate the air
to and from the point of combustion, thereby
rarefying the air and producing a vacuum
30 which causes the atmosphere to flow contin-
ually by its own weight and thoroughly
commingle and change in all parts of the
room, thereby imparting a constant onward
movement or current thereto thoroughly
35 cleansing, renovating and changing the air
in the entire inclosure in which the stove is
used.

A further object is to provide a stove that
will so conduct and direct the travel of the
40 products of combustion as to permit them
to escape through the chimney flue or, if
desired, to divert their course so as to permit
them to flow into the inclosure in which
the stove is used.

45 Another object is to afford facilities for
permitting a part of the products of combus-
tion to escape by way of the chimney flue
and at the same time permit a part to flow
into the room or inclosure in which the stove
50 is placed.

Another object is to provide a means of
ventilating or permitting the products of
combustion to escape from the stove directly
into the room or inclosure instead of per-

mitting them to pass out through the chim- 55
ney pipe flue; said object being accom-
plished when the damper of the chimney pipe
flue is operated to prevent the escape of the
products of combustion therethrough with-
out in any way smothering or checking the 60
flame or affecting the suction or drawing
properties produced by the ordinary natural
draft. This feature has the effect of produc- 65
ing perfect combustion, which eliminates
the disagreeable odor and prevents the at-
mosphere from being impregnated with
poisonous gases.

A further object is to provide a heater that
will consume all of the gases and prevent
any part thereof from escaping within the 70
room or the inclosure in which the stove is
placed and which will perform this function
without the necessity of connecting a pipe
to the chimney flue as is the case when the
ordinary type of heater is used. 75

Another object consists in deflecting the
travel or passage of the products of combus-
tion to force them to travel in a tortuous
path before escaping thereby spreading the
heat radiation over a larger area of the 80
heater.

Further objects comprise an easy and con-
venient means of igniting the gaseous fuel,
safety in operation on account of the flame
being directed toward the rear wall of the 85
heater, and economical operation because of
the double flue system which draws from
above and beneath the point of combustion
of the gaseous fuel.

I attain these and other objects by con- 90
structing and assembling the elements illus-
trated in the accompanying drawing, in
which:

Figure 1 is a front elevation of a heating
stove having this invention applied thereto. 95

Fig. 2 is a vertical central side sectional
elevation of Fig. 1 showing in detail the
assembled arrangement of the invention.

Fig. 3 is a plan view on an enlarged scale
of the top of the stove with the smoke pipe 100
removed.

Fig. 4 is a vertical section on the line
4-4 of Fig. 3.

Fig. 5 is a vertical section on the line
5-5 of Fig. 3, showing a bowl mounted 105
upon the scalloped portion of the flue pipe
connection.

In the drawings, reference numeral 1 de-

lineates the body of the stove, 2 the top, 3 the legs and 4 a foraminated protecting shield which is arranged to cover the opening 5 in the front of the stove. In the interior of the stove body, preferably adjacent to the top, deflectors 6 and 7 are provided and spaced apart, leaving the free ends overlapping each other and extending in opposite directions.

10 A rearwardly extending inclined curved reflector wall 8 is fastened to the inner side walls B of the reflector wall 8 leaving a chamber 9 and being spaced apart from the back wall of the stove body leaves a passageway 10 communicating with the open chamber 11 at a pre-determined point below the deflector 7 preferably in close proximity thereto.

20 A burner 12 is provided which extends across the front of the stove body adjacent to the top of the opening 5. The gas adjustages 13 are formed in the rear portion of the burner 12 so that the natural draft will draw the flame as shown at 14 toward the rear wall of the stove body as clearly shown in Fig. 2. Upon the top 2 of the stove, a hollow member 15 is mounted which is preferably formed U shape.

25 The hollow member is mounted directly over an aperture 16 which communicates with the interior of the stove body. The chamber 17 formed by the hollow member and the top of the stove, is open at the front as indicated at 18 and it is bordered by the hand bracket 19 which is provided with a hand slot 20. The bracket is used when it is desired to transport the stove from place to place.

30 A scalloped pipe connection 21 is provided or made integral with the hollow member to connect the flue pipe 22 to the stove when desired, or in the event that the flue pipe 22 is not used, then to provide means of supporting a vessel for cooking purposes or the like. In Fig. 5 the vessel is indicated by the numeral 23. The scalloped portion of the pipe connection provides escape vents for the products of combustion. The flue pipe connection 21 communicates with the chamber 17 formed by the hollow member and through the opening 16 with the interior of the stove body.

35 To regulate, check and divert the products of combustion through the pipe flue; thence out through the chimney flue, or to permit the products of combustion to pass through the chamber 17 and flow into the room or inclosure in which the stove is placed, a damper 24 is slidably mounted upon the lug ways 25 and 26 and is adapted by hand manipulation to close the passage 27 through which the products of combustion pass into the chimney flue or to open the passage and permit the products of combustion to pass out of the chamber 17 into the

room or inclosure surrounding the stove, if desired.

The handle 28 can be manipulated to slide the damper to the position shown in Fig. 5, thereby opening a passageway from the interior of the stove body directly through the chimney flue into the atmosphere.

40 Attention is called to the fact that air is admitted from beneath the heater into the chamber 9 and it then passes through the 75 passageway 10 commingling with the air in the chamber 11 which is admitted over the top of the burner 12. The gaseous fuel, when ignited, draws the air from beneath and above the burner simultaneously, 80 thereby producing a circulating current of air which accomplishes the desideratum of perfect combustion and the resultant elimination of the odor prevents the impregnation and vitiation of the air which surrounds 85 the heater with poisonous and disagreeable gases.

45 The products of combustion from the burner are conducted out above the passageway 10 around the free ends and spaces 90 between the deflectors into the room or out through the chimney flue if desired, the arrangement of the deflectors forcing the products of combustion to travel in a tortuous path by means of which they cover a 95 larger area of the interior of the stove body giving forth more heat radiation than if they were permitted to escape in a direct line out through the chimney flue. Reference letter A represents the gas supply pipe 100 and reference letter C represents a valve cock.

50 What is claimed is:

1. In a heating apparatus, a body including a front wall formed with an opening, 105 a rear wall, and a top, a curved deflector extending from the front wall adjacent the lower edge of the open end inclining upwardly and rearwardly within the body and terminating in spaced relation to the rear 110 wall, the upper edge of the deflector being approximately in line with the upper edge of the front wall opening, a burner arranged within the body in approximate alinement with the upper edges of the deflector and 115 the front wall opening, and adjacent the front wall, a baffle plate secured to the front wall immediately above the opening and extending transversely the body with its rear wall exceeding the minimum distance 120 between the rear wall and curved deflector, said burner being formed to direct the flame therefrom toward the space intermediate the free ends of the curved deflector and baffle plate but at an angle to the rear wall, whereby air currents are directed 125 through the front wall opening above and below the burner and between the deflector and rear wall wholly to one side of the burner, a hollow member secured to the top 130

of the body and being in communication with the body and with the atmosphere, said member having a passage in parallelism with the top of the body, with the passage 5 opening to the body and having an outlet beyond the body, and a damper in the member to control the atmospheric communication of the body.

2. In a heating apparatus, a body having 10 an open front, an upwardly and rearwardly curved deflector arranged in the body and coextensive in height with the opening in the front, a burner arranged in line with the upper edge of the deflector and the upper edge of the open front, an opening in 15 the body above and to the rear of the burner,

a hollow member independently secured to the top of the body and having an outlet in line with the opening of the top of the body and an outlet passage arranged in 20 parallelism with the top of the body, said outlet passage being in open communication with the opening at the top of the body, and a damper mounted in said member to control communication between said passage 25 and the opening from the hollow member.

In testimony whereof I affix my signature in presence of two witnesses.

BERRY A. BAXTER.
